L. JUDELSO

WASHING MACHINE

Filed Nov. 2, 1922

UNITED STATES PATENT OFFICE.

LOUIS JUDELSOHN, OF NEW YORK, N. Y.

WASHING MACHINE.

Application filed November 2, 1922. Serial No. 598,557.

To all whom it may concern:

Be it known that I, LOUIS JUDELSOHN, a citizen of the United States, residing at the city of New York, in the county of Bronx and State of New York, have invented certain new and useful Improvements in Washing Machines, of which the following is a specification.

This invention relates to washing machines. More particularly, it is directed to the type of washing machine having an interior rotary drum for overturning the wash in the cleansing process, and having a power wringer attached thereto. The object of the invention is to provide a washing machine of this character having a power driven clothes wringer attached thereto and adapted to be operated from the power mechanism for operating the rotary drum, provision being made for either operating the interior drum alone or simultaneously operating both the clothes wringer and the drum as desired.

A further object of the invention is to provide in a washing machine having a wringer attached thereto, a power mechanism of the character and for the purpose described which shall be easy to manipulate and efficient in operation to a high degree. Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawings, in which is shown one of various possible illustrative embodiments of this invention,

Fig. 1 is a vertical elevation of a washing machine with wringer attached embodying this invention;

Fig. 2 is a cross-sectional view taken along line 2—2 of Fig. 1 and showing the power transmission mechanism for operating the wringer and interior rotary drum;

Fig. 3 is a fragmentary view showing the mechanism for transmitting power to the wringer rolls and for reversing the direction thereof;

Fig. 4 is a detailed view cut along line 4—4 of Fig. 2 showing part of the means

for connecting the wringer drive to the main power shaft; and

Fig. 5 is a detailed view taken along line 5—5 of Fig. 1 showing the means for making swinging connection of the clothes wringer to the washing machine.

Referring in detail to the drawing, 10 indicates the outer casing or drum of the washing machine within which operates the usual rotary drum 11 mounted on a shaft 12. 13 indicates the main shaft connected to the prime mover by means of the pulley 14 and belt 15 or connected to the power source in any other suitable manner. The rotary drum 11 is operated from the main shaft 13 by a train of gears 16, 17, 18 suitably arranged and of suitable construction for transmitting the desired motion to the drum. The particular manner of operationally connecting the shaft 12 to the power shaft 13 forms no part of this invention, and any suitable transmission mechanism may be employed for this purpose. Secured at one end of the casing 10, preferably at the end remote from the power end, is a clothes wringer which is indicated generally at 19, and extending longitudinally of the casing 10 is a shaft 20 suitably journaled in bearings 21, 22 adjacent either end of the drum for transmitting the motion from the main shaft to the power drive of the clothes wringer.

This shaft 20 is adapted to be driven from the main shaft by means of a worm 23 driven from a counter-shaft 24 in horizontal alignment with the main shaft 13, and which worm is adapted to operate the gear 25 mounted on the power end of the shaft 20. The worm 23 and gear 25 are housed in a suitable gear box 26 into which extends the shaft 20 through the bearing member 21 formed in the gear box. The shaft 24 is journaled as at 27 in the gear box 26 and extends beyond the latter so as to leave a space 28 between the main shaft and itself. Mounted back of the gear box 26 is a coupling collar 29 having an annular recess 30 formed therein to receive a block member 31. This collar is further provided with a key-way 32 adapted to receive a pin or key 33 extending from the main shaft 13. The shaft 24 has a key-way 34 cut therein adjacent the end projecting from the gear casing for a key 35 which affords positive engagement between the collar 29 and the

shaft 24, as will be readily understood. The collar 29 is adapted to slide on shafts 13 and 24, so that when said collar is moved into position so as to dispose the key-way 32 opposite the pin 33, the latter engages in said key-way and shaft 13 is coupled to shaft 24 so that shaft 20 will then be driven in the manner already described from the main shaft. On the other hand, when the 10 collar 29 is out of engagement with the pin 33 (the position shown in Fig. 2) then the shaft 13 is disconnected from shaft 24 and shaft 20 is stationary while the drum is operated.

15 To facilitate the sliding of the collar 29, I provide a shaft 36 adapted for longitudinal movement in a sleeve 37. The forward end of said shaft is provided with a head member 38 from which extends a pin 39, adapted to engage in an opening 40 in the block 31. Said head member rests against the sleeve 37 and is kept in engaging position with the block 31 by means of a coil spring 40' held between the rear end 25 of the sleeve 37 and a collar 41 on the shaft 36. A hand lever 42 is provided for manipulating the shaft 36 so as to cause the pin 39 mounted eccentrically thereon to rock to and fro in order to slide the coupling collar 29 into and out of engagement with the key 33.

For transmitting the power from shaft 20 to the power drive for the rollers 19^a, 19^b of the wringer, a spiral gear 43 is mounted 35 on shaft 20 adapted to operate a spiral gear 44 mounted on the vertical shaft 45 which is the power shaft for the wringer rollers. From this shaft the motion is transmitted through gear 20^a to either one of the gears 40 20^b or 20^c at right angles thereto, depending upon the position of the clutch 20^c which is adapted to couple either one of said gears with the drive shaft 20^a for operating the rollers. The particular drive mechanism for driving the wringer rollers may be 45 of any suitable character. Preferably the mechanism such as described in my co-pending application, Serial No. 555,947, filed April 12th, 1922, may be employed.

50 Means is provided for swinging the wringer in and out of operative position relative to the washing machine. The wringer itself is mounted on a support 46 adapted to swing in a bracket 47, by means 55 of a sleeve member 49 loose on the shaft 45 and connected to the support 46 at one end and extending through the bracket 47 at the other. Said sleeve member is recessed as at 50 for a bearing block 51 adapted to 60 be urged against the sleeve by means of a screw member 52 operated by a handle 53 (see Fig. 5). By operating the handle 53 the wringer may be maintained in operative or inoperative position by the frictional engagement of the block 51 against the sleeve

49. When it is desired to swing the wringer from one position to the other, the handle 50 is operated so as to move the block 51 out of engagement with the sleeve 49, as will be readily understood.

It will thus be seen that there is provided a device in which the several objects of this invention are achieved and which is well adapted to meet the conditions of practical use.

As various possible embodiments might be made of the above invention and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:—

1. In a washing machine having a power wringer attached thereto, a power shaft for transmitting power to said washing machine, a counter shaft for transmitting power to said wringer, a coupling shaft for coupling said first mentioned shafts to each other, a coupling collar adapted to slide over the power shaft and said coupling shaft, and co-operating means on said power and counter-shafts and said collar for positively connecting said shafts to each other.

2. In a washing machine having a power wringer attached thereto, a power shaft for transmitting power to said washing machine, a counter shaft for transmitting power to said wringer, a coupling shaft for coupling said first mentioned shafts to each other, a coupling collar adapted to slide over the power shaft and said coupling shaft, said collar having a key way formed therein and said power shaft having means adapted to engage in said key way for positively connecting said power shaft to said countershaft.

3. In a washing machine having a power wringer attached thereto, a power shaft for transmitting power to said washing machine, a counter shaft for transmitting power to said wringer, a coupling shaft for coupling said first mentioned shafts to each other, a coupling collar adapted to slide over the power shaft and said coupling shaft, said collar having a key way formed therein and said power shaft having means adapted to engage in said key way for positively connecting said power shaft to said countershaft, and means for moving said coupling collar into and out of engagement with said engaging means on said power shaft.

4. In a washing machine having a power wringer attached thereto, a power shaft for transmitting power to said washing machine, a counter shaft for transmitting

power to said wringer; a coupling shaft for coupling said first mentioned shafts to each other, a coupling collar adapted to slide over the power shaft and said coupling shaft, said collar having a key way formed therein and said power shaft having a key projecting therefrom adapted to engage in said key way for positively connecting said

power shaft to said counter shaft and means for moving said coupling collar into and out of engagement with said key, said means comprising a member engaging said collar and adapted to permit free rotation of said collar. 10

In testimony whereof I affix my signature.
LOUIS JUDELSON.
